UNITED STATES PATENT OFFICE.

CHRISTIAN H. STOELTING, OF CHICAGO, ILLINOIS, ASSIGNOR TO WILLIAM A. VAWTER, OF SAME PLACE.

BINDER.

SPECIFICATION forming part of Letters Patent No. 486,989, dated November 29, 1892.

Application filed June 25, 1892. Serial No. 437,958. (No model.)

To all whom it may concern:

Be it known that I, CHRISTIAN H. STOELTING, of Chicago, in the county of Cook and State of Illinois, have invented certain new and useful Improvements in Binders; and I do hereby declare that the following is a full, clear, and exact description thereof, reference being had to the accompanying drawings, and to the letters of reference marked thereon, which form a part of this specification.

This invention has reference to that class of temporary binders which comprises, in a binder, two covers, rods secured to an edge of one of said covers and adapted to be inserted through suitable openings in the corresponding edge of the other cover, and means for detachably securing or locking said removable cover to said rods at any desired point on said rod, the temporary files being placed over the rods between the covers and bound together by forcing the edges of said covers firmly thereupon and securing or locking said covers in this position.

The present invention consists in the improved means for locking or detachably securing the removable cover of a binder of the class described upon the rods over which the files are placed, and also in the features and details of construction hereinafter described, and specifically pointed out in the claims.

In the drawings, Figure 1 is a perspective view of a temporary binder embodying my invention. Fig. 2 is a top plan view of the removable binding-piece inclosed in canvas and showing the escutcheon-piece. Fig. 3 is a similar view of said binding-piece, the escutcheon plate and canvas being removed. Fig. 4 is a similar view of the same piece, the cap or cover thereof being removed, so as to show the locking-bars, said bars being in their retracted or free position. Fig. 5 is a view thereof similar to Fig. 4, showing the bars in their cast or locked position. Fig. 6 is a sectional view on the line 6-6 of Fig. 2. Fig. 7 illustrates a modified form of the locking device, the bars being retracted. Fig. 8 shows the same modification, the bars being cast. Figs. 9 and 10 illustrate another modification, showing the bars retracted in the former and the bars being cast in the latter

view. Fig. 11 is a transverse sectional view on the line 11-11 of Fig. 5.

In the drawings, A represents the under or lower cover of a temporary file, which may be of any approved construction, with binding-rods B rigidly secured in and projecting laterally from one end thereof.

C represents as a whole the upper cover of a temporary file comprising a cover proper C' and a binding-piece C², united to the cover proper by means of any flexible hinge. In the preferable construction illustrated both covers are inclosed in canvas or other suitable material, the canvas inclosing the upper cover extending continuously over the cover proper C' and the binding-piece C², the opposite sides of said canvas being united by a seam c between said cover proper and said binding-piece, thus providing a suitable and convenient hinge. In the binding-strips C² holes or apertures c' are provided, each so located as to receive one of the binding-rods B.

The construction of the binding-strip C², whereby the same is adapted to be detachably secured to the binding-rods B, is as follows: Said binding-piece is made in two separate parts, a main or body part c² and a cap or cover therefor c³. The body of said binding-strip is preferably made of suitable sheet metal, the turned up parallel sides c⁴ of which are at right angles with the bottom thereof, and thus form a groove or recess C⁵, into the ends of which suitable blocks or filling-pieces c⁵ are fitted flush with the tops of the sides c⁴. The cover or cap c³ for said body portion is preferably constructed, as shown, of suitable sheet metal with edges turned at right angles, forming sides c⁶, adapted to embrace the sides c⁴ of said body portion, the sides c⁶ of said cap extending flush with the under surface of said body portion. The turned-down sides c⁶ of said cap or cover will thus reinforce or strengthen the sides c⁴ of the body portion. It is not essential, however, that said cap be constructed as described, as a flat cap or cover not having the sides c⁶ and adapted to close the top of said recess may be employed if deemed desirable for any reason. The cap or cover is secured to the body portion of the binding-piece by screws or rivets c⁷, the heads

of which will preferably be so made as to be flush with the top of the cover or cap. Holes will also be formed in said cap or cover of the same size as the holes or apertures c' in 5 the body of the binding-piece and in such position relative thereto that the rods B when inserted therethrough will be perpendicular to the sides of said binding-piece. Into the groove C^3 , formed in the body part of the 10 binding-piece c^2 , as above described, are fitted two locking-bars D, both adapted to move longitudinally therein independently of each other. Adjacent to the rods B or to the holes c' , through which said rods pass, said bars D 15 are cut away in such manner as to form inclined surfaces d on said bars, which when said bars are forced in the proper direction will engage the rods D and serve to wedge said bars between the sides of the binding- 20 piece C^2 and said rods, thus clamping said binding-piece firmly in position upon said rods D. Movement of said bars in the opposite direction will likewise disengage them and allow the removal of said binding-piece 25 from or their adjustment upon said rods. In order to permit the movement of said bars relative to the stationary screws or rivets c^7 , said bars are cut away adjacent thereto, as shown at d' , in such manner as to allow desired movement of said bars. Preferably 30 corresponding parts of the two levers are made to register when said bars are in the middle point of their movement, thereby producing greater symmetry in said binding- 35 piece.

In the preferable form of the device illustrated in Figs. 1 to 5 of the drawings, both inclusive, the locking-bars are cast and retracted by means of a key E, having lugs or 40 lateral projections e , adapted to engage notches e' , formed in said locking-bars D, so that as said key is turned it will force said bars positively in opposite directions. A projection e^2 at the end of said key is fitted to a 45 circular hole e^3 in the bottom of the main part of said binding-piece and acts as a pivot on which said key turns, said key being thereby held against bodily longitudinal movement with either of said bars and insuring 50 that said bars will be moved equal distances in opposite directions by the turning thereof. In order that said key may not interfere with the longitudinal movement of said lock-bars, the corners of the notches e' 55 are cut away or beveled, as shown at e^4 . Moreover, in order to allow the insertion of said key into operative position, it is necessary that when said bars are fully cast or retracted the beveled sides of the notches of 60 said bars, respectively, which pass nearest to the axis of rotation of said key shall not approach nearer thereto than a distance equal to one-half of the thickness of said key. Preferably the angle of said bevel will be about 65 forty-five degrees to the sides of the locking-bars D. A circular hole e^5 , having a diameter equal to the width of the key between the

outer edges of the projections e thereof, is provided in the cover C^3 , which likewise is to allow the insertion of said key into operative 70 position.

In the preferable form of the device springs are applied to the locking-bars in such manner as to tend normally to cast said springs or to maintain them when cast in such cast 75 position. In the construction shown wire springs F are applied, one to an end of each of said bars, said springs being inserted between the respective ends of said locking-bars and the pieces c^5 , which close the ends of 80 the grooves in such manner that they will tend to cast said locking-bars. This construction has two obvious advantages: First, when the locking-bars are cast they will counteract the effect of any jar, as from dropping 85 the binder, which might tend to disengage the frictional contact of the locking-bars and binding-rods, and, second, when said bars are retracted said springs tend to maintain them normally in position to permit the insertion 90 of the key to cast said springs and lock the binder.

In the preferable form of the device an escutcheon-plate G is provided, said plate being secured to the upper surface of the binding-piece after the same has been assembled and inclosed in the canvas covering, whereby it is attached to the cover proper, said plate being apertured to correspond with the binding-piece. This escutcheon-plate is primarily for the purpose of a finish to the binding-piece, serving to cover raw, ragged, or drawn edges of the canvas when unfinished holes are cut therein, as around the keyhole, the holes for the passage of the binding-rods B, 10 and the like.

In the form of the device illustrated in Figs. 1 to 6, both inclusive, said escutcheon-plate is constructed and answers the purpose as follows: The hole in said plate for allowing the insertion of the plate comprises inner circular sections g , having a diameter equal to the width of the key above the flanges e of the key E, and outer circular sections g' , sufficiently large to admit the passage therethrough of the projections e of the key. Moreover, the width of the lugs e is equal to the distance between the inner surface of the bottom of the binding-piece and of the escutcheon-plate, respectively. Thus when said key is turned after being inserted in the lock the lugs e thereof will project beneath the edges of the inner sections g . Moreover, the relation of the sections g and g' to each other and to the notches e' in the locking-bar is such as to allow the insertion of the key into operative position when the locking-bars D are in their normal retracted position and such that as said key is turned beyond the point necessary to fully retract the locking-bars the projections e of the key will pass beneath the sections g of the escutcheon-plate, so that said key will form a handle whereby the removable cover C may be con-

veniently handled. The relation of said parts is such, moreover, that when said cover is locked in position upon the binding-rods B the key may be removed from the lock and again inserted when it is desired to retract or unlock said bars.

In Figs. 7 and 8 of the drawings a modification of the means for casting and retracting the bolts is illustrated. In these views, as in Figs. 1 to 6, C^2 is the main part of the binding-piece C^2 . B are the binding-rods, to which it is to be secured, and D the locking-bars. In this case, however, the locking-bars are operated as follows: Mounted in said binding-piece C^2 is a pinion E, which engages rack-teeth e at the bottom of a recess formed in said bars adjacent to said pinion, said recesses being of such length as to permit desired movement of said locking-bars and the edges thereof preferably registering when said bars are at the middle point of their movement. The pinion E is rigidly mounted upon a shaft or axis e' , which has bearings in the top and bottom, respectively, of the binding-piece C^2 . This shaft projects through the top of said binding-piece and a handle e^2 is secured thereto, whereby said pinion may be rotated, so as to cast or retract said locking-bars D.

Figs. 9 and 10 illustrate still another modification of the means for operating the locking-bars. In this construction the locking-bars D are operated by means of links e , each secured at one end to one of said locking-bars D and at the other to a collar or flange E, rigid upon a shaft e' , mounted in the binding-piece C^2 , the points of attachment with the collar E being eccentric to the axis of the shaft e' , to which said collar is secured, said links being so attached as to move said bars equal distances. The shaft or axis e' projects above the top of the binding-piece C^2 and a handle e^2 is attached thereto for operating the same. In the two forms of the device last-mentioned springs are applied thereto tending to cast the locking-bars, as in the form of the device first described and for the same purposes. There being no loose key in the modified forms of the device, no provision is made in constructing the escutcheon-plate for holding the same in operative position. In any form of the device the escutcheon-plate is desirably secured to the binding-piece by means of the screws or rivets c^7 , which extend through said escutcheon-plate, and also by other screws or rivets c^8 , binding said plate and binding-piece together near their ends. Moreover, in all forms of the device shown the binding-rods B will be provided near their upper ends with annular grooves adapted to receive the locking-bars and permit of their being fully cast. The edges of said grooves will thus form shoulders, which will hold said binding-piece positively in position. This is designed for use only when the file is full and is to be permanently locked.

It is obviously not essential that two wedging-surfaces be employed to clamp both bind-

ing rods, as practically the same effect can be produced by the use of a single wedging-surface, as would be the case were the locking-bars D cut off at the point x, as indicated in Figs. 4 and 5 of the drawings. I do not therefore wish to limit myself to the use of a device with two wedging-surfaces adapted to engage each rod B.

I claim—

1. A temporary binder comprising the combination, with a cover and rods secured thereto, of a binding-piece provided with holes or perforations adapted to receive said rods, locking-bars longitudinally movable in said binding-piece, having surfaces adapted to engage said rods and lock or clamp said binding-piece thereto, and means for actuating said locking-bars, substantially as described.

2. A temporary binder comprising the combination, with a cover and rods secured thereto, of a binding-piece provided with holes or perforations adapted to receive said rods, movable locking-bars in said binding-piece, having surfaces adapted to engage said rods and lock or clamp said binding-piece thereto, and means for positively actuating said locking-bars, and a spring applied to each of said locking-bars, tending to cast and retain said bars normally in a locked position, substantially as described.

3. A temporary binder comprising the combination, with a cover and rods secured thereto, of a binding-piece provided with holes or perforations through which said rods pass and having, also, longitudinally-movable locking-bars the surfaces of which are adapted to engage said rods to clamp said binding-piece thereto, notches in the edges of said locking-bars, and a key provided with lateral projections to engage said notches to actuate said bars, substantially as described.

4. A temporary binder comprising the combination, with a cover and rods secured thereto, of a binding-piece provided with holes or perforations through which said rods pass and provided, also, with longitudinally-movable locking-bars the surfaces of which are adapted to engage said rods and to clamp said binding-piece thereto, notches in the edges of said locking-bars, a key provided with lateral projections adapted to engage said notches to actuate said bars, and a spring applied to each of said bars, tending to cast and to retain said bars normally in a locked position and against accidental unlocking, substantially as described.

5. In a temporary binder, the combination, with the lower cover and rods secured thereto, of a binding-piece comprising a body piece or part having a longitudinal groove, longitudinally-movable locking-bars located within said groove, each bar having a wedge-shaped portion at one end, holes or perforations through said binding-piece adapted to receive said rods, and means for actuating said bars, whereby the wedge-shaped portions of said locking-bars are moved longitudinally

between said rods and the sides of said groove and in engagement therewith to lock the parts together, substantially as described.

6. In a temporary binder, the combination, 5 with the lower cover and binding-rods secured thereto, of a binding-piece comprising a body-piece having a longitudinal groove in its upper side, longitudinally-movable locking-bars located therein, a cap or cover for 10 said binding-piece provided with sides or flanges adapted to embrace the edges of the binding-piece proper, holes or perforations in said binding-piece and cover adapted to receive the binding-rods, said locking-bars being provided with surfaces adapted to wedge 15 between the sides of the groove and the binding-rods as the locking-bars are moved, and means for actuating said locking-bars, substantially as described.

20 7. The combination, with the binding-strip of a temporary binder, comprising a binding-piece proper and a cap or cover therefor, of a canvas covering for said binding-piece, whereby the top cover proper is flexibly attached to 25 said binding-piece, and a detachable escutcheon-plate secured to the upper surface of said binding-piece outside of said canvas covering, substantially as described.

8. In a temporary binder, the combination, 30 with the lower cover, rods secured therein, and a binding-piece comprising a grooved binding-piece proper and a cap or cover there-

for, locking-bars fitted to and longitudinally movable in the groove formed in said binding-piece, and a key for operating said locking-bars, said key being provided with lateral projections, of an escutcheon-plate secured to the upper surface of said binding-piece and a hole in said plate, said hole comprising outer sections to allow the insertion 4 of the key into operative position and inner sections which project inwardly beyond the ends of the lateral projections of the key and are adapted to prevent the removal of the key from the binding-piece when said lateral projections are inserted thereunder, substantially as described.

9. In a temporary binder, the combination, with the under cover, the binding-rods secured therein, a binding-piece, holes therein 5 adapted to receive the binding-rods, and longitudinally-movable locking-bars mounted in said binding-piece, of annular grooves at the upper ends of said binding-rods, adapted to engage said locking-bars, and means for actuating said bars, substantially as described.

In testimony that I claim the foregoing as my invention I affix my signature in presence of two witnesses.

CHRISTIAN H. STOELTING.
